US00D890271S

(12) **United States Design Patent** (10) **Patent No.:** **US D890,271 S**
Carmichael et al. (45) **Date of Patent:** **** Jul. 14, 2020**

(54) **CARRIAGE FOR EXERCISE RACK**

(71) Applicant: **Coulter Ventures LLC**, Columbus, OH (US)

(72) Inventors: **James Carmichael**, Hilliard, OH (US); **Ahmik Jones**, Upper Arlington, OH (US); **Bill Henniger**, Columbus, OH (US)

(73) Assignee: **Coulter Ventures, LLC.**, Columbus, OH (US)

(**) Term: **15 Years**

(21) Appl. No.: **29/661,400**

(22) Filed: **Aug. 27, 2018**

(51) LOC (12) Cl. **21-02**

(52) U.S. Cl.

USPC **D21/686**

(58) **Field of Classification Search**

(57) **CLAIM**

The ornamental design for a carriage for exercise rack, as shown and described.

DESCRIPTION

FIG. 1 is a top, front, left perspective view of a carriage for exercise rack showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a bottom, front, right perspective view thereof; and,

FIG. 9 is a top, front, left perspective view thereof shown in a condition of use.

The broken lines shown adjacent to the shaded areas are to show portions of the carriage for exercise rack which are not part of the claimed design. The additional broken lines shown in FIG. 9 are to show environmental structure and are not part of the claimed design.

1 Claim, 6 Drawing Sheets
